Primary Examiner — Cynthia Ramirez*Assistant Examiner* — L. Martinez-Rivera(74) *Attorney, Agent, or Firm* — Vorys, Sater, Seymour
and Pease LLP(57) **CLAIM**The ornamental design for a window component extrusion,
as shown and described.**DESCRIPTION**

FIG. 1 is an isometric view of a window component extrusion according to the present disclosure.

FIG. 2 is a left side view of the window component extrusion of FIG. 1.

FIG. 3 is a right side view of the window component extrusion of FIG. 1.

FIG. 4 is a rear view of the window component extrusion of FIG. 1.

FIG. 5 is a front view of the window component extrusion of FIG. 1.

FIG. 6 is a top view of the window component extrusion of FIG. 1; and,

FIG. 7 is a bottom view of the window component extrusion of FIG. 1.

The window component extrusion is shown with two parallel dash-dot break lines that represent the bounds of the claim. The appearance of any portion of the article between the break lines forms no part of the claimed design.
